UNITED STATES PATENT OFFICE

172,891

BRACELET OR THE LIKE

Louis Kramer, New York, N. Y., assignor to
Kramer Jewelry Creations, Inc., New York,
N. Y.

Application March 4, 1954, Serial No. 29,334

Term of patent 3½ years

(Cl. D45—4)

To all whom it may concern:

Be it known that I, Louis Kramer, a citizen of the United States of America, residing in New York City, county of New York, and State of New York, have invented a new, original, and ornamental Design for a Bracelet or the like, of which the following is a specification, reference being had to the accompanying drawing, forming part thereof.

Fig. 1 is a plan view of a bracelet or the like, showing my new design.

Fig. 2 is an edge view thereof.

I claim:

The ornamental design for a bracelet or the like, substantially as shown.
